UNITED STATES PATENT OFFICE.

DAVILA S. DU BRUL, OF CINCINNATI, OHIO, ASSIGNOR TO THE MILLER, DU BRUL & PETERS MANUFACTURING COMPANY, OF CINCINNATI, OHIO.

MATRIX.

Application filed July 17, 1919. Serial No. 311,420.

To all whom it may concern:

Be it known that I, DAVILA S. DU BRUL, a citizen of the United States, and resident of Cincinnati, in the county of Hamilton and State of Ohio, have invented certain new and useful Improvements in a Matrix, of which the following is a specification.

The present invention relates to a matrix or mold which is designed primarily for used with cigar bunching machines, and is an improvement on the matrix set forth in the patent to F. C. Miller, No. 567,350 of September 8, 1896.

As heretofore practised, matrices of the character described have usually been made with their side walls adjustable to effect an increase or decrease in the area of the matrix opening, which would result in changing the shape of the mold and increasing or decreasing the size of the object to be molded. It has been found that, while a proportional adjustment, which was mechanically very good, could be obtained with the matrices now employed, the tobacco did not run into these matrices in proportion to the shape of the opening. Consequently, the present design has been appropriated to give a plurality of independent adjustments at different points in one side wall of the mold opening, and to provide these adjustments by constructing the said wall of the mold of a plurality of sections, and having these sections wide enough to cover considerably more of the length of the cigar to be molded on each section than did the separate tumblers on the previous construction.

Another object of the invention is to so construct the matrix, particularly the adjusting means, whereby a wider range is obtained, enabling a number of shapes to be had with the same matrix.

While the device contemplated by the invention will be hereinafter described as especially adapted for cigar bunching machines, it should in no way be construed as limited to this particular use, as it may readily find expression in a matrix which may be used to advantage in other co-related arts. Furthermore, while the matrix in its preferred form consists in constructing one side wall of the matrix opening with a plurality of independently adjustable sections, it is to be understood that the opposite side wall in some instances, should

conditions require it, can be also constructed with like sections.

Referring to the accompanying drawing, which illustrates the preferred features of the invention, the figure is a perspective view of the matrix constructed in accordance with the invention.

5 represents the frame, which is of a size to conveniently adapt it to power bunching machines. The matrix opening 6 is open throughout the depth of the frame 5 and is formed in the frame 5 by means of the rigid side wall 7 and the opposite side wall, which is composed of a plurality of independently adjustable sections comprising the blocks 8. Overlying the rigid side wall 7 is a metal plate 9, which is preferably of tool steel and acts in conjunction with a similar plate at the bottom of the hopper under which the matrix slides. These two plates act to shear off the tobacco as the matrix leaves the machines, as is common in cigar bunching machines. Underlying the frame 5 is a metal plate 10, which extends partially across the bottom of the matrix, thereby providing a smooth, even bearing surface for the blocks 8. Each of the blocks 8 is provided on its under side with a recessed portion 11, in which is received the metal strip 12, which strip limits the amount of adjustment of the blocks. Carried by the frame 5 is a bar 13, which extends longitudinally along the edge of the matrix, with the portion intermediate its ends offset from the edge of the matrix, and providing a bearing for each of the adjusting means 14 of the blocks, these adjusting means preferably comprising elongated set screws passing through the bar 13 with their ends embedded in the blocks.

It will be seen that any one of the blocks 8 may be adjusted independently of the others, by manipulating any one of the separate adjusting means 14. For instance, by turning the screw clockwise, its screw-threaded engagement with the block would tend to draw the same away from the matrix opening, thus varying the area of the opening at this particular point; by turning the screw anti-clockwise it would tend to push the block toward the opening, resulting in decreasing the area of the opening at this particular point.

As is common in cigar bunching machines, the matrix is shiftable to two positions, in

one position it forms a section of the hopper and is located above the flat bottom plate and while in this position has pressed down into it from the upper part of the 5 hopper the desired quantity of filler. It is then shifted to the second position off of the bottom plate thereby leaving the bottom of the matrix open above the rolling apron and in this position a plunger presses the 10 tobacco down through the open bottomed matrix onto the rolling apron. After having been acted upon by the rolling apron in the usual manner, the cigar bunch is carried therefrom by means of jaws, and 15 deposited through these jaws with the aid of another plunger into the mold. In the movement from the first to the second position which takes place usually in a direction normal to the longitudinal axis 20 of the matrix, the tobacco in the matrix is sheared off the tobacco column in the hopper by the knife edge (shown at 9 in the drawing) acting in conjunction with a similar knife edge at the bottom of the

hopper proper thus determining the amount 25 of tobacco which goes into the matrix and therefrom to the rolling apron.

Claims:

1. In a device of the character described, a frame, means carried by the frame for adjusting the area of the matrix opening, comprising a plurality of independently adjustable, horizontally sliding blocks, said blocks forming one side wall of the matrix, means on the frame for limiting the adjustment of the blocks, a bar carried by the frame, and means carried by each one of the blocks having an adjustable engagement with said bar for selectively adjusting any one of the blocks. 30 35

2. A matrix for cigar bunching machines having one of its side walls rigidly fixed in a frame and its opposite side wall slidably mounted in the frame, said slidably mounted wall composed of a plurality of selectively 40 45 adjustable sections whereby the contour of the matrix opening may be changed.
